LAMINATED METAL BARREL

Stewart S. Battles, Chicago, Ill., assignor, by
mesne assignments, to Borg-Warner Corpora-
tion, Chicago, Ill., a corporation of Illinois

Application January 14, 1933, Serial No. 651,716

6 Claims. (Cl. 220—63)

This invention relates to metal containers and will be described as incorporated in a barrel formed of composite metal.

An object of this invention is the provision 5 of a metal barrel formed of sheet material, the sheet metal including an inwardly disposed lamination of non-corrodible material, preferably an alloy for resisting possible chemical actions of the contents of the barrel on the inner surface, 10 and a lamination of other metal preferably a mild steel disposed outwardly.

Another object is the provision of a barrel 15 having a portion formed of two composite sheets of metal each including a non-corrodible portion, such that the completed barrel will have no cor- 20 rodible portions disposed inwardly and such that the sheets forming the barrel will be welded together by a deposit of metal on the inside of the barrel without causing an appreciable irregular- 25 ity on the inner surface of the barrel.

The metal employed in the construction of barrels in accordance with this invention is preferably of the kind, and made by the process set forth in United States Letters Patent No. 25 1,868,749 issued July 26, 1932 to Stephen L. Ingersoll, to which reference is hereby made for a detailed description of the metal and process of forming the composite sheets.

Other objects and advantages of this invention 30 will become apparent from the following detail description with reference to the accompanying drawing.

On the drawing:

Figure 1 is an elevational view of a barrel 35 incorporating my invention, a portion of the same being shown in section to better disclose the construction of the same.

Figure 2 is an enlarged fragmentary section taken on the line II—II of Figure 1.

Figure 3 is a section similar to Figure 2 but 40 illustrating a modified form of construction, and

Figure 4 is an enlarged section similar to Figure 2 but illustrating a further modification of the invention.

As shown on the drawing:

The barrel 5 preferably comprises end or base 45 portions 6 and 7 and a container portion 8. The container portion is preferably formed of two deformed sheets 9 and 10 of metal. Each sheet 50 9 and 10 was preferably formed from a single disc of metal by suitable drawing operations. Each sheet 9 and 10 comprises an outwardly disposed lamination 11 consisting of a mild steel, and an inwardly disposed lamination 12 prefer- 55 ably consisting of stainless steel or other non-

corrodible chromium steel alloy. The two laminations are intimately welded together throughout their engaging areas forming a single sheet of composite metal. The term "composite" as used in this specification and in the claims has 5 reference to this specific type of sheet metal construction as set forth in the above mentioned patent to Stephen L. Ingersoll. The marginal portions of the sheets 9 and 10 are flared outwardly at 13 and 14 to provide an annular space 10 which is preferably filled with a deposit of stainless steel as indicated at 15 to form a permanent weld for securing the flared portions 13 and 14 together in alignment and with the inner surface of the deposited metal forming the weld, 15 being in substantial alignment with the inner surface of the barrel to avoid appreciable irregularities and crevices into which the contents of the barrel might gain access and make cleaning difficult. 20

The edge portions 17 and 18 of the sheets 9 and 10 are permanently interlocked, to relieve 25 excessive strain at the welded joint, and to provide an annular reinforcement around the central portion of the barrel. In the form of the invention shown in Figure 3, the edge portions of the flared margins are rolled together instead of being folded together as shown in Figure 2, thereby forming a relatively rigid annular roll 21 extending around the barrel and interlocking 30 the sheets 9 and 10 together. In the modification shown in Figure 4, the flared margins 13 and 14 are very short and the outwardly disposed edges are permanently welded together by 35 an annular deposit 22 of metal. In this modification, the exterior weld 22 is preferably of a tough mild steel, whereas the inner weld 15 is a suitable corrosion-resisting alloy or stainless steel. 40

Referring now to Figure 1, there are provided 45 annual corrugations 26 and 27 for reinforcing the sheet metal of which the barrel is composed, in order that the barrel may be as light as possible and sufficiently rigid to withstand rough handling and rolling when filled. One end of the barrel is provided with an opening 28 through which the barrel may be filled with beverages such as beer and the like. The ends of the barrel 31 and 32 are preferably dome-shaped and are substantially arcuate where they join the 50 side portions of the barrel, thus avoiding all sharp corners and recesses which would be difficult to clean. The end or base portions 6 and 7 are preferably substantially cylindrical, fitting upon the ends of the container portion and be- 55

ing permanently welded in position as indicated at 33 and 34. The extreme end edges of the base portion may be rolled as at 36 and 37 to reinforce the same and prevent bending when being 5 handled.

The base portions 6 and 7 are provided with corrugations 42 and 43 which engage the container portion adjacent the welds 33 and 34 respectively, and serve as a guide in positioning the 10 base portions as well as to provide reinforcement to withstand shock and relieve the welds of undue stress.

It will be understood from the foregoing description that this invention is susceptible of various forms and modifications without departing from the principle of the same. I desire, therefore, that the patent to be granted hereon shall not be restricted in any manner, except as necessitated by the prior art.

20 I claim as my invention:

1. A metal container comprising a pair of superimposed tub-like members having continuous inside surfaces of a corrosion resistant alloy backed by an outside integral lamination of tough 25 metal bonded thereto at all points, outwardly flanged abutting edges around the periphery of said tub-like members defining a groove between the tubs, a weld of corrosion resistant alloy in said groove joining the tubs together and additional 30 reinforcing structure cooperating with the outside of said tubs for holding the tubs in assembled relation.

2. A metal container comprising a pair of superimposed tub members having continuous inside surfaces of stainless steel backed by an integral layer of mild steel bonded thereto at all 35 points, outwardly flanged abutting edges around the peripheries of each of said tub members defining a groove between the tubs, a weld of stainless steel in said groove joining the tubs together and an outside weld of mild steel between the 40 abutting edges of the tubs for reinforcing the inside weld.

3. A barrel including complemental composite 45 sheet metal tub sections having an interior surface of non-corrosive metal and an exterior surface of a different metal, said sections having opposed contiguous peripheral flanges turned outwardly thereby effecting an internal annular 50 groove circumscribing said barrel, means for

bonding said tub sections together comprising a welding body of non-corrosive metal filling such groove flushly with the interior of said barrel, and additional bonding means exteriorly of said barrel and in registry with such groove. 5

4. A barrel comprising complemental composite sheet metal tub sections having an interior surface of non-corrosive metal and an exterior surface of a different metal, said sections having opposed contiguous peripheral flanges turned 10 outwardly thereby effecting an internal annular groove circumscribing said barrel, means for bonding said tub sections together comprising a welding body of non-corrosive metal filling such groove flushly with the interior of said barrel, and 15 additional structure augmenting the bond of said welding body, said structure comprising said flanges disposed in an interlocking relation exteriorly of said barrel.

5. A barrel comprising complemental composite sheet metal tub sections having an interior surface of non-corrosive metal and an exterior surface of a different metal, said sections having opposed contiguous peripheral flanges turned 25 outwardly thereby effecting an internal annular groove circumscribing said barrel, means for bonding said tub sections together comprising a welding body of non-corrosive metal filling such groove flushly with the interior of said barrel, and additional structure augmenting the bond of said 30 welding body, said structure comprising a reinforcing loop substantially circular in cross section and formed of said flanges disposed in an interlocking relation exteriorly of said barrel. 35

6. A barrel comprising complemental composite sheet metal tub sections having an interior surface of non-corrosive metal and an exterior surface of a different metal, said sections having opposed contiguous peripheral flanges turned outwardly thereby effecting an internal annular 40 groove circumscribing said barrel, means for bonding said tub sections together comprising a welding body of non-corrosive metal filling such groove flushly with the interior of said barrel, and additional structure augmenting the bond of said 45 welding body, said structure comprising a reinforcing band flat in cross section and formed of said flanges disposed in an interlocking relation exteriorly of said barrel.

STEWART S. BATTLES. 50
